CLAIM

The ornamental design for a protective cover for bag and luggage, as shown and described.

DESCRIPTION

FIG. 1 is a front, right and top perspective view of a protective cover for bag and luggage, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another front, right and top perspective view of the protective cover for bag and luggage in an open state.

The dot-dash broken lines shown in the drawings depict stitching of the protective cover for bag and luggage that form part of the claimed design.
